UNITED STATES PATENT OFFICE

JOHN O. CARR, OF CHICAGO, ILLINOIS, ASSIGNOR TO TELETYPE CORPORATION, OF CHICAGO, ILLINOIS, A CORPORATION OF DELAWARE

REMOTE CONTROL SYSTEM

Application filed February 8, 1932. Serial No. 591,534.

This invention relates to methods and systems for remote control and more particularly to methods and systems for remote control applied to radio communication systems. 5 Systems in which remote units are selectively controlled to perform various operations practically eliminate the use of attendants at points where remote-control apparatus are located, by providing control of these 10 apparatus at a centralized point where a single operator may have under his direct control all of these remotely disposed apparatus. This not only reduces costs, but provides systems of great flexibility because of 15 this common control. Such systems are moreover essential in cases where the controlled apparatus is located at a position not easily accessible by an operator or which, for any special reasons, it is desired to be 20 remotely controlled.

Remote control systems, however, have encountered difficulties due to interference from extraneous sources on the signalling system which have, in some instances, caused incorrect 25 operation of the remote unit. These interferences may be due to stray currents from other signalling systems or to deliberate intrusion on the system by unauthorized individuals. In wire circuits, this may be done by 30 tapping signalling wires. In radio transmission to which the system of this invention is particularly adapted, it may be done by transmitting inimical control operations on the same wave length.

35 The objects of the present invention are a remote-control system and its method of operation which are extremely simple, possesses considerable flexibility and are effective against intrusion.

40 This invention provides means for sending telegraphic signals in rapid succession by radiant energy, and provides further means for receiving, recording, interpreting and again recording those signals which represent 45 transmitted intelligence. It provides first-record means for all received signals but provides second-record means for only a limited number of the many possible codes of signals. Modification means is also provided for the interpreting devices whereby

the number of predetermined codes to be transmitted to the second-record devices may be reduced, thereby decreasing the likelihood that chance signals or deliberate-interference signals will have any influence upon the 55 second-record means and thereby upon the work to be done by the transmitted intelligence.

A clear understanding of the invention may be had from the following description, taken 60 in conjunction with the accompanying drawings, wherein,

Fig. 1 is a circuit diagram of the transmitter in a radio system embodying this invention. 65

Fig. 2 is a circuit diagram of a receiver illustrating one adaption of this invention.

Fig. 3 is a table of codes for the system of Fig. 2.

Fig. 4 is a circuit diagram of a modification 70 of the selecting circuits of Fig. 2.

Fig. 5 is a table of codes for the system of Fig. 4.

An operating station or central control station 10 is connected to a remote station 11 75 by means of a radio channel. At station 10, a keyboard 12 having keys 1 to 8 and "C O" is arranged according to principles of automatic telegraphy to control selectively the closing of a combination of contacts 13 in 80 various permutations according to the signal to be transmitted. In addition to the selectively operated contacts 13, the keyboard is also provided with a normally closed stop contact 14 which keeps the energy of bat-

tery 15 on the wire 16 and is opened to transmit a start signal to the remote station in a manner to be described more fully hereinafter. This keyboard may be of the type shown in the patent to Krum et al., 1,374,152, 85 issued April 5, 1921, although it will be understood that any other transmitter, as for example, a tape controlled, single contact transmitter may be used. In the particular transmitter chosen to illustrate the invention, 90 the operating contacts for a code are sequentially associated with the signalling system in a manner well known in the art and a group code of unit signals is transmitted. Although as shown the keys carry designa- 100

tions of numerals and letters, it will be understood that for the purpose of the present invention, designations of the desired remote operations will preferably appear on the 5 key levers.

An amplifier and radio transmitter 17 with antenna 18 convert battery signals impressed upon wire 16 into radiant energy signals upon the antenna 18.

10 At the remote station 11, a receiving antenna 21 is connected to an amplifier-detector 22, the output circuit of which controls a relay 23 which in turn by its contacts controls the current through a distributor 24.

15 The signal codes sent to the wire 16 by the keys of keyboard 12 may be as indicated in Fig. 3. In Fig. 3, the seven time-periods of a code are shown by seven parallel columns, in which the columns "S" indicates the starting signal, columns "1, 2, 3, 4, 5" indicate the signals for the selective code, and column "6" indicates the "stop" signal, constituting a resumption of the idle condition of the line circuit. In Fig. 3, the idle condition is the

25 continuous connection of battery 15 to the wire 16 at station 10, the transmission of no radiant energy from antenna 18 to antenna 21 and the continuous engagement of the armature of relay 23 with its back contact S at station 11. In Fig. 3 each horizontal line shows at the left the label of a key in the keyboard 12 of Fig. 1, and at the right of the label in the row are shown in the seven columns the closed or open condition of the

30 contacts 13—14 in each of the seven time-periods represented individually by the seven columns. Thus it is shown that upon the operation of key 2 in keyboard 12, a code will be sent comprising one time-period of 40 no-current on wire 16, followed by two time-periods of current on wire 16, followed by three time-periods of no-current on wire 16, followed by the normal idle condition of current on wire 16.

45 The distributor 24 comprises two segment rings 27 and 28, over which a brush 29 rotates to distribute the received impulses in a manner to be described. The brush 29 is mounted on and rotatable with a shaft connected through a friction clutch (not shown) to the rotating member of a continuously operating motor (not shown). The brush 29 is normally in operative engagement with a stop-armature 30. The armature 30 is pivoted to the framework (not shown) and is normally held in engagement with the brush 29 by a spring, one end of which is secured to the armature 30 of an electromagnet 31 and the other to the framework.

55 The operation of the armature 30 is controlled by the electromagnet 31, which is connected from ground over the conductor 32 to the stop segment 33 on the distributor 24. The front contact M of the relay 23 is connected to segment 34 of the distributor

24. With the distributor in the position shown, the circuit for the starting magnet 31 may be completed from ground through battery, over front contact M of relay 23, segment 34, brush 29, segment 33, conductor 70 32, electromagnet 31 and return through ground. The electromagnet 31 being normally non-energized permits its armature 30 to engage the brush 29 and the distributor brush arm is held from rotation, thus slipping the friction clutch of the continuously rotating motor.

75 As illustrated, four of the other segments 36, 37, 38, 39 of the ring 28 are electrically connected to individual selector relays 41, 42, 43 and 44, respectively, and segment 40 is connected to and through the armatures and contacts of the four selector relays. The remaining segment 45 of the ring 28 is connected to an unlocking relay 46 and its companion segment is connected to battery.

80 Individual to the selector relays are locking armature-contacts 48 and operating armatures 50 to 60, inclusive.

85 The nine contact points of the operating armatures 56 to 60 of the selector-relay 44 are connected to eight operating relays or second-record relays 61 to 68 and a clearing relay or enabling relay 69. Each of the relays 61 to 68 has a pair of locking contacts 70 which close a locking circuit from earth through the relay winding, then contacts 70, wire 71, lock-out relay or disabling relay 72, wire 73 and contacts 73' of clearing relay 69 to battery. Each of the relays 61 to 68 has also a pair 90 of operating contacts 74 which close a circuit from battery through contacts 75 of clearing relay 69, then through contacts 74 severally to the work-units 81 to 88 severally, and to earth. The divide relay 72 opens 105 the operating circuits of all relays 61 to 68 but not of the clearing relay 69.

110 In operation, briefly, the controlling station 10 of Fig. 1 sends a start-stop code which at the remote station 11 of Fig. 2 operates a relay-selector which selects and operates one of the second-record relays 61 to 68. The selected relay locks, and thereby operates the divide relay 72 which disables all relays eligible to the selector except the clearing relay 69. The second-record relay also energizes one of the work-units 81 to 88. As long as the system is left in this condition, thirty-two permutation signals may be sent upon the five permutation time-periods of columns 1 to 5 in Fig. 3, but no signals upon the antenna 21 will have effect except the clearing signal which will operate the relay 69 and will release all relays 61 to 68 after which a second code may be sent to 115 select the same or another second-record relay.

120 It is obvious that the system is open to interference by any of a plurality of code combinations of signals upon antenna 21 130

when the divide relay 72 is not operated, but is open to but one code, the clearing code, when the divide relay 72 is operated.

To utilize further this feature of safety in the operation of the system, a non-operating second-record unit is provided as shown by the relay 67 wherein the locking current through the relay 67 operates the divide-relay 72 but wherein the omission of the earth connection upon the unit 87 renders the unit 87 ineffective. During intervals when it is not desired to operate any work-unit, the divide relay 72 may be held charged by selecting the second-record relay 67, thus operating the relay 72 to guard other second-record relays from operation until the clearing relay 69 shall have been operated. The sending of the next operating code then is prefaced by the clearing code, which is a full code including the starting signal, as shown in Fig. 3, the system of this invention being thus less open to willful interference than any system which might be conditioned by a single signal impulse even though that single impulse must have a proper time relation with a synchronous distributor.

In detail, the operation of effecting the energization of the work-unit 82, for example, is as follows:

The operator at the station 10 depresses key 2 of the keyboard 12. This starts the sender 13—14 and a start-stop telegraphic code is sent over the wire 16 according to the code 2 of Fig. 3, as follows, open-closed-closed-open-open-open, after which the normally closed condition or stop-condition will be resumed and maintained until a subsequent code is sent.

The normal condition of the antennæ 18 and 21 being no-current, the code sent will result in a unit-length start signal of radiant energy, followed by a two-unit time-period of no-current signal, followed by a three-unit-length signal of radiant energy.

The start signal operates relay 23 to close its contact M, which operates magnet 31 and the brush 29 starts. During the two-unit interval of no-signal, the relay 23 holds its contact S closed and the brush 29 charges the two selector relays 41 and 42, which lock through contact of relay 46. During the three-unit signal the relay 23 closes its contact M. Brush 29 passes segments 38 and 39 without charging the relays 43 and 44. This point in the progress of the brush 29 marks the completion of selection, since the operated condition of selector relays 41 and 42 jointly with the non-operated condition of selector relays 43 and 44 effects the preparation of the selective circuit of relay 62 in the selector, subject to closure at the third contact of relay 72 and at contact 40 of the distributor and at the contact M of the line relay 23. The relay 72 at this time will be

found uncharged and with its contacts closed.

The selection thus prepared is rendered effective by an executive signal from the control station through the relay 23. The executive signal is indicated in column 5 of Fig. 3 and it is timed at station 11 by the engagement of brush 29 with the segment 40, completing the selector circuit, which charges the second-record relay 62 over the circuit from relay 23, contact M, brush 29, segment 40, armature 50 and front contact, armature 51 and front contact, armature 53 and back contact, third contact of relay 72, wire 89, armature 57 and back contact, wire 90, relay 62 and earth. Relay 62 operates and locks up over the circuit from contact 73' of relay 69, wire 73, relay 72, wire 71, contact 70 of relay 62, winding of relay 62 and earth, thereby operating the relay 72 and locking both relays 62 and 72. Relay 72 disables all relays 61 and 63 to 68. Relay 62 also closes its contact 74 and energizes the work-unit 82. At segment 45, the brush 29 closes a circuit to energize the relay 46 and thus to unlock the used relays of the selector-relays 41 to 44.

The next effective code will be the clearing code which is identical with code 2 except that all relays 41, 42, 43, 44 are charged and relay 69 is operated momentarily over wire 91.

Double selector

In Fig. 4 is shown a modification of Fig. 2 in which the codes are longer and are more difficult of simulation by interference. The reference numerals of Fig. 2 are repeated where the parts are identical. Segments 106, 107, 108, 109 are added to the ring 28 of the distributor 24. Associated with the added segments are the added selector relays 111, 112, 113, 114 with their locking points 48, and with their operating armatures 120 to 130. The second-record relays 61 to 68 have separate windings for their locking circuits.

For operation with the remote station of Fig. 4, the controlling station 10 of Fig. 1 will require additional contacts 13.

The code for operating the system of Fig. 4 is shown in Fig. 5. It is a start-stop code comprising nine permutation signals combined with a start signal, shown in column "S" and a stop signal shown in column 10.

In the code as shown, the units 5, 6, 7 and 8 are duplicates of the units 1, 2, 3 and 4, respectively, thus making the relay armatures 120 to 130 duplicates of armatures 50 to 60 respectively, but this is not a limitation of this invention. Any permutation of signals may be used and the relay armatures and contacts connected to correspond to the code.

A feature of the invention is dividing the selector relays into two groups, arranging

the contacts of each group in the form of a circuit fan, connecting the operating relays between the two fans and confining the contacts of the divide relay to the connectors of 5 one of the fans, since thereby the total number of fan and divide contacts may be made a minimum.

In operation, the system of Fig. 4 is similar to the system of Fig. 2 except for the 10 longer code group and for the tracing of the operating paths through the circuit fans. To charge the second-record relay 62, code-2 of Fig. 5 is sent and received, thus charging and locking the selector relays 41, 42, 111, 15 112. The relay 62 then is charged over the circuit (Fig. 4) from relay 23 front contact, brush 29, segment 40, armature 50 and front contact, armature 51 and front contact, armature 53 and back contact, right-inner contact of relay 72, wire 89, armature 57 and back contact, wire 90, right winding of relay 62, back contact and armature 127, back contact and armature 123, front contact and armature 121, front contact and armature 20 120 to earth. Relay 62 operates and locks by its left hand winding and armature over a circuit from battery through winding of relay 72, wire 73, left contacts 73' of clearing relay 69, left contacts (70) of charged relay 25 62, left winding of relay 62, and to earth, thus operating the relay 72 and locking both relays, 72 and 62. Relay 72 disables all second-record relays 61 and 63 to 68. Relay 62 also closes its right contacts 72 and energizes 30 35 its work unit, not shown in Fig. 4. At segment 45 the brush 29 closes an obvious circuit to energize relay 46 to unlock the used selector relays.

Variations and developments may be made 40 without departing from the spirit of the invention. The radiant transmission may be a continuous signal with brief breaks. The selector may be of any type. A relay selector has been shown because it is a simple 45 form of selector where the total number of selections is small. The synchronism may be of any type such as the start-stop method of synchronism or the continuous method of synchronism.

50 Although the invention has been described in connection with a specific form thereof, it will be understood that it has further application and it is not intended to be limited by the specific embodiment shown for illustration.

The invention claimed is:

1. The method of controlling remote apparatus which comprises sending a start-stop conditioning code for conditioning the remote 55 apparatus to respond to codes other than a start-stop conditioning code, sending a start-stop selecting code for initiating a desired work at the remote apparatus, sending a start-stop clearing code for terminating the initiated work, and sending a start-stop lock-

out code for disabling the remote apparatus from responding to any code other than a start-stop conditioning code.

2. The method of controlling remote apparatus which comprises sending a code for 70 conditioning the remote apparatus to respond to other codes, sending a code for initiating a desired work at the remote apparatus, sending a code for terminating the initiated work, and sending a code for disabling the remote apparatus from responding to any code other than a code for conditioning, each and every of said codes being a group code of uniform length and being composed of unit signals and comprising a selecting signal followed 75 by an executive signal, the selecting signals being variant in all codes and the executive signal being uniform in a plurality of codes.

3. The method of controlling remote apparatus which comprises sending a code for 80 conditioning the remote apparatus to respond to other codes, sending a code for initiating a desired work at the remote apparatus, sending a code for terminating the initiated work, and sending a code for disabling the remote 85 apparatus from responding to any code other than a code for conditioning, each and every of said codes being a group code and all of said codes being of uniform length.

4. In a remote-control system, operating 90 relays, a lock-out relay for disabling said operating relays, a clearing relay for enabling said operating relays, and a selector responsive to line signals for selectively rendering said several relays individually responsive each to a code combination of line signals.

5. In a remote-control system, a control station, a transmitter at said station adapted to send code signals, each such code signal comprising a selective component followed by 105 an executive component, and a remote apparatus comprising an operating relay, a lock-out relay for disabling said operating relay, a clearing relay for enabling said operating relay, and a selector responsive to the selective component of a code signal for selectively rendering said several relays responsive to the executive component of the code 110 signal.

6. In a remote-control system, a control station, a remote station, a selector at said remote station and responsive to signals from said control station, a plurality of relays for selection in response to remote control codes 115 of signals, selector circuits individual to said relays for selecting them, said circuits each normally open at a line-signal-control point, lock-out means responsive to code signals from said control station for opening and closing all of said selector circuits at a local-control point, means in said selector for preparing one of said selector circuits at all points other than at the local-control point and at the line-signal control point, and exec- 120 125 130

- utive means for closing said selector circuits at the line-signal control point in response to a specific signal, whereby the successive operation of said lock-out means, said selector and said executive means may close completely a 5 desired selector circuit and effect the energization of one of said relays.
7. In a remote-control system, an operating relay, a first relay for enabling said operating 10 relay, a second relay for disabling said operating relay, and a selector comprising a distributor and relays responsive to remote-control signals for initiating the operation of said operating relay, said second relay operating 15 also to terminate the operation of said operating relay in response to remote-control signals.
8. In a remote-control system, an operating relay, a local selecting circuit for said 20 relay, means for enabling and disabling said selecting circuit, a selector responsive to remote-control signals for controlling said means and for closing said selecting circuit to initiate the operation of said operating 25 relay, and a local locking circuit for locking said operating relay, and for controlling said means.
9. In a remote-control system, operating 30 relays, selecting circuits for said relays, a disabling relay for opening said selecting circuits, a relay for enabling said selecting circuits, a selector responsive to remote-control signals for closing one of said selecting circuits to initiate the operation of one of said 35 operating relays, and a local locking circuit for said operating relay, said disabling relay operated by said local locking circuit to open said selecting circuits.
10. In a remote-control system, a control 40 station, a remote station, a selector at said remote station and responsive to signals from said control station, a plurality of operating relays for operation by remote control, selector circuits individual to said operating relays 45 and through contacts in said selector, a lock-out relay for opening said circuits, a further operating relay for operation by remote-control, and a further selector circuit individual to said further operating relay and through 50 contacts in said selector and operable by said selector while said lock-out relay is in operated condition.
11. In a remote-control system, a control 55 station, a remote station, a selector at said remote station and responsive to signals from said control station, a plurality of relays for operation by remote control, selector circuits individual to said relays and through contacts in said selector, and a disabling relay 60 for opening said selector circuits, said disabling relay operated by an operating one of said relays.
12. In a remote-control system, a relay 65 selector comprising a plurality of relays divided into two groups, the contacts of the re-
- lays of each group connected in fan formation, electromagnetic units to be selected connected between the terminal conductors of the two fans, and a disabling relay having its points connected in the conductors of one only 70 of the fans.
13. In a remote-control system, a relay selector comprising a plurality of relays divided into two groups, the contacts of the relays of each group connected in fan formation, 75 and electromagnetic units to be selected connected between the terminal conductors of the two fans.
14. In a remote-control system, a plurality of relays, selector circuits for energizing said 80 relays, a lock-out device for disabling said selector circuits, a clearing device for re-enabling said selector circuits, and a set of selector relays operable repeatedly by variant signal codes to operate said clearing device and 85 to select one of said selector circuits.
15. In a remote-control system, a plurality of relays, selector circuits individual to said relays, a selector responsive to codes of signals for selecting one of said circuits, a lock-out 90 device for disabling said selector circuits and operable by any of said relays whereby but one relay may be operated at one time, and a clearing device operable by said selector in response to a code of signals for re-enabling 95 said selector circuits, all of said codes being of uniform length.
16. In a remote-control system, a selector operable by remote control, a plurality of relays, selector circuits for said relays, a local 100 device for disabling all of said selector circuits and operable by any one of said relays, whereby but one of said relays may be operated at one time, and a device operable by said selector for re-enabling said selector circuits. 105
17. In a remote-control system, a plurality of devices, selecting apparatus responsive to received code combinations of impulse conditions for variably operating said devices, 110 said devices being normally non-effective in response to the selective operation of said selectors operating in accordance with received combinations of impulses, and a device common to all of said devices operated by 115 said selectors in accordance with a predetermined code combination of impulses for rendering said other devices responsive thereafter in accordance with the operation of said selectors by said received code combinations of impulse conditions. 120
18. In a remote-control system, a plurality of devices, selecting apparatus responsive to received code combinations of impulse conditions for selecting one of said devices for operation, said devices being normally non-responsive to the operation of said selecting apparatus, a common means operated by said selecting apparatus in accordance with a predetermined code combination of impulse conditions. 125
- 130

ditions for rendering said devices operative, any one of said devices upon operation remaining operative independent of said common means, and further means controlled by 5 said devices for rendering said devices non-responsive to further code combinations of impulse conditions whereby only one of said devices is operated at a time.

19. In a remote-control system, a plurality 10 of relays, selecting apparatus responsive to received code combinations of impulse conditions for selecting one of said relays for operation, said relays however being normally non-responsive to the operation of said selectors, a further relay operated by said selectors in accordance with a predetermined code combination of impulse conditions for rendering said first relays operative, and means controlled by said selected relay for rendering 15 20 any similar relay non-responsive to its individual code combination of impulse con-

ditions whereby only one of said relays is operated at a time.

20. In a remote control system, a plurality of devices, selecting apparatus responsive to received code combinations of impulse conditions for selecting one of said devices for operation, said devices being normally non-responsive to the operation of said selecting apparatus, a common means operated by said selecting apparatus in accordance with a predetermined code combination of impulse conditions for rendering said devices operative, any one of said devices upon operation remaining operated independently of said common means, and further means controlled by 70 75 80 said devices for rendering said devices non-responsive to further code combinations of impulse conditions whereby only one of said devices is operated at a time.

In testimony whereof I affix my signature. 85
